ELECTRICAL STANDOFF INSULATOR

Roger B. White, Cleveland Heights, Ohio, assignor to The Glastic Corporation, Cleveland, Ohio, a corporation of Ohio

Application June 30, 1958, Serial No. 51,588

Term of patent 14 years

(Cl. D26—10)

FIG. 1

FIG. 2

FIG. 3

Figure 1 is a perspective view of an electrical standoff insulator showing my new design;

Figure 2 is a side elevational view, the opposite side being substantially a mirror image thereof;

Figure 3 is a side elevational view taken at approximately 90° to the view shown in Figure 2, the opposite side being substantially a mirror image thereof.

I claim:

The ornamental design for an electrical standoff insulator, as shown and described.
